Des. 202,489
Patented Oct. 5, 1965

202,489

MOTORCYCLE WINDSHIELD

Ted Zbikowski, Detroit, and John L. Marchello, Ann Arbor, Mich., assignors to Joseph Buegeleisen Co., Southfield, Mich.

Filed Mar. 14, 1963, Ser. No. 73, 969

Term of patent 14 years

(Cl. D90—1)

FIG. 6

FIG. 9

FIG. 8

FIG. 1 is a perspective view, taken from the right side, of a motorcycle windshield, showing our new design.

FIG. 2 is a rear elevational view thereof.

FIG. 3 is a right side elevational view thereof, the left side being the same in appearance.

FIG. 4 is a top plan view thereof.

FIGS. 5 and 6 are each perspective views, taken from the right side, showing a modification.

FIG. 7 is a rear elevational view of the modification of FIG. 5, and

FIG. 8 is a right side elevational view thereof, the left side being the same in appearance, and

FIG. 9 is a top plan view thereof.

We claim:

The ornamental design for motorcycle windshield, as shown and described.
